UNITED STATES PATENT OFFICE.

JACOB E. BLOOM, OF CINCINNATI, OHIO.

BOOT OR SHOE.

SPECIFICATION forming part of Letters Patent No. 249,738, dated November 22, 1881.

Application filed April 1, 1881. (No model.)

To all whom it may concern:

Be it known that I, JACOB E. BLOOM, a citizen of the United States, residing at Cincinnati, in the county of Hamilton and State of Ohio, have invented certain new and useful Improvements in Boots, Shoes, &c.; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to improvements in boots, shoes, &c.; and it consists in a boot or shoe provided with a lining and middle sole of a non-conductor of heat; and to effect this I make said lining and middle sole of asbestos cloth or felting, or of suitably-prepared glass-cloth.

It is well known that asbestos is a good non-conductor of heat, and that glass-cloth has a very low conducting power. I may also use for the purposes described a composition of asbestos spread upon oiled skin or other water-proof substance.

In the drawings, Figures 1 and 2 are elevations, partly in section, of a shoe provided with a middle sole and lining of the non-conducting material described. Fig. 3 is an enlarged section of the sole of the shoe; and Fig. 4, a section of the shoe, showing the middle sole and lining with the asbestos felting. Fig. 5 is a middle sole provided with the asbestos felting, ready to be put into the shoe.

In the several figures, A represents the asbestos felting of the middle sole of the boot or shoe; B, the bottom sole; C, the middle sole.

The felting and glass-cloth are made water-proof in a manner that will form the subject of a separate application.

In summer the soles of boots and shoes become heated by contact with the earth or pavements, and as leather is a good conductor of heat the heat is conveyed to the feet and be-

comes a source of annoyance, often causing the feet to swell and blister. Now, by placing the non-conducting material between the foot and the sole of the shoe, the heat is confined to the outer sole, and only the normal heat of the foot is retained. Again, in winter the leather becomes cold and the feet chilled and often frosted or frozen, with all the evils consequent thereto; but this is also prevented in the same way by my invention, for the normal heat of the foot is not conducted off by the leather, but is retained within the shoe or boot. Now, by using the water-proofed asbestos, or the oiled skin prepared with the asbestos composition, I make boots or shoes water-proof, and at the same time conserve the other functions relating to heat and cold, as just described. Boots and shoes made in this manner are especially valuable in the army and navy, where the men are subject to great exposure of heat and cold and dampness. It is also of great value to hunters and miners.

It is not necessary that a boot or shoe be made heavy in order to avoid heat, cold, and dampness. On the contrary, a light boot or shoe provided with the asbestos lining and middle sole can be worn as well in winter as in summer and the feet be protected.

Having thus described my invention, what I claim as new, and desire to secure by Letters Patent, is—

1. A boot or shoe having a lining and middle sole of asbestos, substantially as described, and for the purpose set forth.
2. A shoe provided with the middle sole, A, and lining A', of asbestos or composition of asbestos, substantially as described, and for the purpose set forth.

In testimony whereof I affix my signature in presence of two witnesses.

J. E. BLOOM.
